US0D1061279S

(12) **United States Design Patent** (10) **Patent No.:** **US D1,061,279 S**
(45) **Date of Patent:** **** Feb. 11, 2025**

(54) **DIGITAL THERMOMETER**

(71) Applicant: **Hetaida Technology Co., Ltd.**,
Dongguan (CN)

(72) Inventor: **Zhenguang Chen**, Dongguan (CN)

(73) Assignee: **HETAIDA TECHNOLOGY CO., LTD.**,
Guangdong (CN)

(**) Term: **15 Years**

(21) Appl. No.: **29/876,213**

(22) Filed: **May 18, 2023**

(51) LOC (15) Cl. **10-04**

(52) U.S. Cl.

USPC **D10/57**

(57) **CLAIM**

The ornamental design for a digital thermometer, as shown and described.

DESCRIPTION

FIG. 1 is a perspective view of a digital thermometer showing my present design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
